R. TOLOOKJIAN

ROTARY BRUSH

Filed April 19, 1923

INVENTOR.
Richard Tolookjian.
BY Richard D. Owen.

ATTORNEY.

UNITED STATES PATENT OFFICE.

RICHARD TOLOOKJIAN, OF PATERSON, NEW JERSEY.

ROTARY BRUSH.

Application filed April 19, 1923. Serial No. 633,224.

To all whom it may concern:

Be it known that I, RICHARD TOLOOKJIAN, a citizen of the United States, residing at Paterson, in the county of Passaic and State 5 of New Jersey, have invented certain new and useful Improvements in Rotary Brushes, of which the following is a specification.

This invention relates to rotary brushes and more particularly to a novel and improved fountain brush wherein the cleaning element is rotated and impelled by a current of water or air from any source of supply.

One of the objects of my invention is to 15 provide a rotary driven fountain brush including a stationary cleaning head and chamber for receiving powdered or soap shavings to produce a lather thus permitting the cleaning elements to be reversed 20 for use on the surface to be cleaned at the discretion of the operator.

Another object of my invention is to provide a combination fountain brush which is extremely simple in construction, easily 25 assembled, highly efficient in operation and use, practical, durable, applicable for universal use and for different uses and one that is particularly designed with due regard for its cheap manufacture whereby 30 the commercial possibilities are greatly enhanced.

I accomplish the above objects and others which will be more readily understood when considered in connection with the accompanying drawings forming a part of 35 this application and wherein, I have illustrated a preferred embodiment by way of example and wherein:

Figure 1 is a sectional view through the 40 fountain brush.

Figure 2 is a sectional view taken on the line 2—2 of Figure 1.

Figure 3 is a further section taken on the line 3—3 of Figure 1.

Referring now to the drawings, wherein 45 like reference characters designate corresponding parts throughout the several views, 5 designates a conventional type of handle having a central bore 6 therethrough, 50 said handle being adapted to receive the end 7 of a flexible tube or pipe through which a jet of water or air may be introduced to propel the rotary element in the manner further to be described. The handle is formed preferably integral with

an enlarged head designated in its entirety by numeral 8 which forms a housing with the end 9 of a casing that carries the rotary element and the brushing element therein. The housing is provided with an annular 60 channel 10 which communicates with the bore 6 through an annular substantially right angle passage 11 and also forms a bearing for a hub 12 to which a plurality of radially disposed curved vanes 13 are 65 connected. The hub 12 is rigidly mounted on the end of a shaft 14 which is preferably of wire, said shaft supporting the rotary cleaning element 15 thereon as clearly shown by Figure 1 of the drawing. The ends of 70 the shaft 14 are preferably mounted for easy rotation on ball bearing 16 in the curved end 17 of the casing and the housing above referred to. A curved plate 18 in the casing constitutes the bottom of what 75 I term, a sub-chamber 19, confined below the curved top 20, in which the bristles 21 are secured as shown. It should also be noted that a passage 22 communicating with the chamber 19 and the chamber 10 permits 80 the water to circulate and mix with the soap powder or soap shavings to produce a lather. It will be seen particularly when referring to Figure 3 that a small passage 85 23 is provided to permit the water to flow out of the chamber 19 after it mixes with the soap, so that the operator may reverse the brush and utilize either the rotating or the stationary bristles on the surface to be cleaned. The casing is held and secured 90 to the handle by a plurality of screws or other fastening elements 25 which may be easily removed when it is desired to disassemble the brush or introduce the soap powder or soap shavings into the chamber 95 19. Of course, if so desired, the soap may be dispensed with in a brush of this character. From this construction, it will be readily seen that as the water enters the bore of the handle and passes into contact with the vanes 13, a rotary motion will be imparted to the shaft and consequently, the cleaning element 15 will be rotated.

The rotary element 15 is so positioned 100 and mounted that when the handle and casing are disconnected, it may be replaced without affecting the remaining construction. The hub and the vanes carried thereby may be removed from the shaft 14 when a new brush is to be used. In the same man- 110

ner, the casing and the permanently secured bristles 16 may be replaced without affecting the remaining construction.

While I have illustrated and described my invention with some degree of particularity, I realize that in practice various alterations therein may be made. I therefore reserve the right and privilege of changing the form of the details of construction or the arrangement of the correlated parts without affecting the spirit of the invention or the scope of the appended claims.

Having thus described my invention, what I claim as new and desire to secure by United States Letters Patent is:—

1. A rotary brush comprising a casing having a soap chamber, a handle connected to the casing and forming a housing at one end therewith, a rotary element mounted in the housing, said housing having passages communicating with the soap chamber and interior of the handle respectively, means permitting the escape of water from the soap chamber and a cleaning element sup-

ported by the casing and housing and operable upon the rotation of the rotary element.

2. A rotary brush comprising a casing having a soap chamber, a handle connected to the casing, a head formed with the handle and constituting a housing with the end of the casing, a rotary cleaning element having a shaft supported within the casing, one end of the shaft extending into the housing, a rotary element secured on the end of said shaft and disposed within the housing, means for permitting the escape of water from the soap chamber and passages communicating between the housing, soap chamber and handle respectively to revolve the cleaning element when a jet of water or air is directed through the handle.

In testimony whereof I affix my signature in presence of two witnesses.

RICHARD TOLOOKJIAN. [L. S.]
